UNITED STATES PATENT OFFICE.

JOHN A. MILLER, OF GLENDALE, CALIFORNIA, ASSIGNOR, BY MESNE ASSIGNMENTS, TO UNION SWITCH & SIGNAL COMPANY, OF SWISSVALE, PENNSYLVANIA, A CORPORATION OF PENNSYLVANIA.

SYSTEM OF RAILWAY SIGNALING AND TRAIN CONTROL.

Application filed June 25, 1920, Serial No. 391,790. Renewed July 19, 1927.

The object of this invention is to provide a system of railway signaling and train control, applicable to either single track or double track electric railways. My invention contemplates and provides certain combinations of apparatus and circuits whereby high frequency alternating currents are employed for the purpose of controlling both road-way and train-carried signals to afford appropriate indications of conditions of safety, caution and danger for the guidance of the motormen in charge of the trains operating on the railways aforesaid.

My invention furthermore contemplates the provision, in combination with the train-carried signals, of means for causing the sounding of an audible signal and the application of the brakes prior to the entry of the car or train, equipped with the improvements of my invention, into an occupied block, and for causing a second application of brakes if, in the first instance, the motorman releases the brakes and proceeds despite the danger indication.

Other objects and advantages of the system shown and described herein will appear as the following detailed description progresses.

In the accompanying drawings,

Figure 1 is a diagrammatic representation of a trolley wire or third rail of an electric railway, said trolley wire or third rail being divided into block sections and suitably connected for co-operation with the signaling equipment of my invention.

Figure 2 is a diagrammatic representation of my invention applied to one track of a double track railway, wherein signals are employed on the movable units, and

Figure 3 is a similar view illustrating my invention as it may be employed in a railway wherein traffic moves in both directions over a single track.

Similar characters of reference refer to similar parts throughout the several views.

Referring first to Figure 1, at 1 I have illustrated a conductor which may be regarded as being a trolley wire or third rail co-extensive with the running rails of an electric railway. This trolley wire or third rail, as the case may be, is divided into block sections A, B, C, D, E and F by insulation

joints 2. Insulation joints 2 are bridged by choke coils 3 which permit the passage of propulsion current impressed upon the conductor 1, but effectively prevent the passage of the high frequency signaling currents presently to be mentioned.

I have not deemed it necessary to illustrate the means for impressing propulsion current upon the conductor 1, as suitable arrangements for this purpose are well known in the art to which my invention relates. Each insulation joint 2 is furthermore bridged by a plurality (in the present instance two) of by-passes P, each by-pass being adjusted with regard to its capacity and inductance to permit the passage of a high frequency current of a definite frequency and to preclude the passage of currents of different frequencies. For convenience I provided each reference letter P with a subscript indicating the particular frequency which the corresponding by-pass is adjusted to pass.

Reference letters G indicate generators of high frequency current, each of said generators arranged to impress a current of a definite frequency upon one of the blocks of the conductor 1, through a transformer T. Condensers e are included in the circuits of the transformer secondaries to prevent the propulsion current from being short-circuited to ground through the transformer secondaries. The sources of high frequency current G may be of any approved and well-known type, and for that reason have been indicated in the accompanying drawings by circles.

For convenience, I have provided each reference letter G with a subscript indicating the particular frequency which its connected generator is intended to impress upon the block section of the conductor 1 with which said generator is associated. In the system of Figure 1, I employ generators delivering frequencies of 5,000, 8,000 and 10,000. In Figure 1, the direction of travel is indicated by an arrow and it is to be understood that each of the generators is so connected as to impress a definite high frequency current upon a block of conductor 1 at its "exit" or "far" end.

Under operating conditions, generators G

are continuously in operation. For the moment disregarding the presence of a car in any block, it will be seen that by virtue of the tuning of the several by-passes P and the fact that I employ generators of the three different frequencies noted on the drawings, each block of the conductor 1 is normally excited with high frequency currents of three different frequencies. In other words, each 10 block section of conductor 1 is normally excited with the high frequency current impressed thereon by its associated high frequency generator G and by virtue of the tuned by-passes P is excited with the high 15 frequency current delivered by the high frequency generator of the next block in advance and is furthermore excited with the high frequency current delivered by the high frequency current generator associated with 20 the second block in advance thereof.

Adjacent the ends of the blocks of conductor 1 are way-side signals consisting of the signal poles S , each of which is provided with visual signals which may be in the form 25 of green, yellow and red lamps indicated by reference letters G , Y and R , respectively. Energization of any one of the green lamps, of course, indicates that the motorman may proceed past that lamp and into the next 30 block with entire safety. The energization of a yellow lamp indicates that he may proceed but slowly and with caution, and the energization of the red lamp indicates that it is dangerous to proceed. The several 35 lamps of each pole S derive their energizing current from a common battery 4 and are controlled by the armatures 5 and 6 of relays R' and R^2 . The circuit connections of the several lamps are such that when both 40 armatures 5 and 6 are attracted or, in other words, lie against their respective front contacts, the green (safety) lamp is lighted, when the armature 5 lies against its back contact and the armature 6 is attracted, the 45 yellow (caution) lamp is lighted, and when armature 6 lies against its back contact the red (danger) lamp is lighted.

Relays R' and R^2 in each instance are connected with high frequency detectors of 50 the three-element vacuum-valve type, the detectors connected with relays R' being designated V' and the detectors connected with relays R^2 being designated V^2 . The proper elements of detectors V' and V^2 are in each 55 instance connected with the secondaries of transformers TR . The primary of each of the transformers TR has one end thereof grounded and its other end connected to the adjacent block of the trolley wire or third 60 rail 1 by a conductor in which is interposed a condenser to prevent the propulsion current from being short-circuited to ground through the primary of the transformer. It will be noted that the tuning of the trans- 65 formers TR is of the parallel resonance type.

or in other words, the condensers which are adjusted with respect to the inductance of the several transformer primaries to tune the latter are connected in parallel with the said transformer primaries. I have found 70 that a parallel resonant circuit offers an extremely high impedance to the passage of the current of the frequency to which it is tuned, and in this respect differs radically 75 from a series resonant circuit. For convenience I have designated the frequency for which each transformer is adjusted by a suitable subscript.

Before considering the operation of the circuits and apparatus, shown in Figure 1, 80 let me refer briefly to the electrical equipment of the car, shown in Figure 2. It will be noted that the car is provided with a trolley 7 from which the propulsion current is led through conductor 8 to the usual circuit breaker, and thence through the controller and motor to the rails in the usual manner. Attention is directed to the fact that a choke coil 9 is interposed in conductor 8 to prevent any of the high frequency current from being short-circuited through the propulsion circuit. The portions of the car equipment with which we are most concerned at present are the several transformers TRX , the several primaries of which are tuned in series resonance to frequencies of 5,000, 8,000 and 10,000. One terminal of the primary of each of the transformers TRX is grounded to the car wheels, while the other end is connected to trolley 7 90 through a connection common to the several transformer primaries in which is interposed a condenser to prevent short-circuiting of the propulsion current through the transformer primaries. It will be noted that the 95 condensers which constitute the capacities by which the transformer primaries are tuned to their respective frequencies are connected in series with the said transformer primaries.

Preliminary to explaining the operation of the circuits and apparatus of Figure 1, I will briefly refer to certain phenomena which account for the practicability of the present invention. A conductor, such as a trolley 100 wire, having distributed inductance and capacity, may be tuned to respond to a particular frequency that may be impressed upon it. It has been discovered that if two series resonant circuits be connected between such a conductor and the ground, the one of said series resonant circuits nearest the source will absorb practically all of the energy, leaving little or none of the energy to traverse the series resonant circuit more remote 115 from the source. The trolley 7 and any one of the primaries of transformers TRX of Figure 2, together with its capacity, in series, constitutes a series resonant circuit which, when connected between the trolley wire and 120 125 130

the rails in any one block, absorbs all of the energy of the frequency to which the transformer primary is tuned and prevents any other correspondingly tuned circuit more remote from the source of such high frequency current (which may be a part of a car equipment or part of a road-way signaling equipment), from receiving any of the high frequency current. It is to be remembered that the primaries of the transformers TR associated with the road-way signals form parts of parallel resonant circuits, offering comparatively high impedance to the passage of currents of the frequency to which it is tuned, while the primaries of the movable unit-carried transformers TRX are connected in series resonant circuits, each of which offers a comparatively low impedance to the passage of the current of the frequency to which it is tuned. It is a fact that in series resonance tuning, when perfect resonance is obtained, the impedance of the circuit is reduced practically to the ohmic resistance of the circuit. It will be understood that the several parallel resonant circuits comprising the primaries of the transformers TR of Figure 1 will absorb but a very small amount of energy. On the other hand, each of the series resonant circuits comprising a primary of one of the transformers TRX of Figure 2 acts as a short-circuit for the particular frequency current to which it is tuned. It is because of these differing characteristics of parallel resonant circuits and series resonant circuits that it is possible to actuate a road-way signal with but small absorption of energy, and to utilize a series resonant circuit on a movable unit for the purpose of short-circuiting all of the high frequency current for which the series resonant circuit is tuned.

Referring now to Figure 1, it will be observed that a movable unit M is indicated as being located in block D. The relays R' and R² used in connection with the road-way signal at the entrance to block D are de-energized because their respective actuating frequencies from generator G₈₀₀₀ of block C and generator G₁₀₀₀₀ of block D are cut off by the series resonance circuits of the movable unit M. Since both relays are de-energized, lamp R at the entrance to block D is lighted, due to the fact that the armature of each of said relays lies against its back contact. The presence of the movable unit M in block D in no way deprives the transformer TR₅₀₀₀ at the entrance to block E of its current of 5000 frequency, but it does deprive the transformer TR₁₀₀₀₀ of its current of 10,000 frequency. Consequently, the relay R² at the entrance to block E remains energized while the relay R' at the same point is de-energized. This relation of the relays results in the energization of the yellow lamp at the entrance to block E. This yellow or

caution lamp of course, indicates to any motorman approaching the entrance to block E that he should proceed with caution, because there is a movable unit in block D.

As the movable unit M enters block C, 70 high frequency current from generator G₁₀₀₀₀ of block D will be restored into blocks D and E. This will result in the energization of relay R' at the entrance to block E, thereby giving a clear indication at the entrance to 75 block E. Relay R² at the entrance to block D will also be energized, thereby substituting a caution indication for the danger indication at the entrance to block D. Simultaneously with this action the signal at the entrance to block C will display a danger indication, because the series resonant circuits of the movable unit M are now absorbing all of the high frequency currents from generator G₅₀₀₀ of block B and generator G₈₀₀₀ of 85 block C, this of course resulting in the de-energization of relays R' and R² at the entrance to block C.

In so far as concerns the trolley wire, the insulation joints thereof, the by-passes at the 90 block ends, the roadway signals and appurtenant equipment, the arrangement shown in Figure 2 may be regarded as identical with that of Figure 1. In order to afford room for proper illustration of the circuits 95 of the movable unit, it has been necessary in Figure 2 to illustrate the road-way signals and appurtenant equipment by mere symbols. Referring particularly to the circuits of the movable unit, which is occupying 100 block F of the trolley wire 1, it will be noted that the secondaries of the tuned transformers TRX₅₀₀₀, TRX₈₀₀₀ and TRX_{10,000} are connected with vacuum tube detectors V³, V⁴ and V⁵, which in turn are electrically 105 connected with relays R³, R⁴, and R⁵.

The movable unit shown in block F which is receiving high frequency currents from generator G₈₀₀₀ of block F, generator G₅₀₀₀ of block E and generator G_{10,000} of block D, 110 has its relays R³, R⁴ and R⁵ closed. These three relays being closed, master relay 85 will be energized, its circuit being closed from battery 56, through lead 55, armature 31 of relay R⁵, lead 49, armature 26 of relay R⁴, lead 42, armature 21 of relay R³, leads 90 and 88, winding 85A, leads 84 and 61, back to battery. Since green signal lamp G is connected in parallel with winding 85A, it is now lighted to indicate safety. The train line valve X is held closed by solenoid 60, the circuit including which proceeds from battery 56, through lead 57, armature 67, lead 73, the winding 60 and thence through leads 58 and 61 back to battery 56. In a similar manner the whistle valve Z is held closed by the solenoid 59, the circuit of which is traced from battery 56, through lead 57, armature 68, lead 71, solenoid winding 59, leads 58 and 61, back 125 130

to battery 56. Safety conditions are displayed on the movable unit and the whistle and train line valves are held closed so long as the three transformers TR_{5000} , TR_{8000} , and 5 $TR_{10,000}$ of the movable unit are receiving currents of the frequencies to which they are tuned.

Assume a movable unit to be located in block C as indicated. High frequency current from generator G_{8000} of block C will be cut off from the anterior portion of block C and entirely from blocks D and E. Moreover the high frequency current from generator G_{5000} of block B will be cut off from the anterior portion of block C and entirely from block D.

Assume now that the movable unit shown in block E proceeds into block E. Since high frequency current of generator G_{8000} 20 of block C is no longer present in block E, relay R^4 will be de-energized, causing the green signal lamp G to be de-energized. The master relay 85, however, will continue to remain energized from battery 56, 25 through lead 55, armature 32, lead 50, armature 27, lead 44 (relay R^4 being de-energized, the armature 27 lies against its back contact), armature 22, leads 91, 86 and 89, 30 through winding 85B and thence through leads 92, 84 and 61, back to battery 56. Since yellow signal lamp Y is in parallel with winding 85B the caution indication will now be given.

Assume now that the movable unit proceeds through block E and into block D. Since high frequency current from generator G_{5000} of block B and generator G_{8000} of block C will both be cut off from block D, 35 relays R^3 and R^4 will be both de-energized. 40 Master relay 85 will also be de-energized and yellow signal lamp Y extinguished. Red signal lamp R will then be lighted, its circuit being traced from battery 56, through lead 57, armature 67 (relay R^3 being de-energized), lead 87, through red lamp R and thence through lead 61, back to battery 56. The opening of master relay 85 will de-energize the train line and whistle 45 valve solenoids 60 and 59, thereby applying the brakes and sounding the whistle of the movable unit in the usual manner.

Sometimes the driver of the movable unit desires to proceed slowly despite the indication of danger. To do this he must release the brakes by closing the train line valve. To close the train line valve, he closes push button 80A which closes the circuit of relay 82 from battery 56, through 55 lead 55, armature 34, lead 93; armature 69, contact 70, lead 78, push button 80A, relay winding 82, leads 83, 84 and 61, back to the battery 56. When the push button is released, relay 82 is held closed through its armature 66 and lead 81 which form a 60 bridge around push button 80A. The train

line valve is closed by solenoid winding 60, the circuit of the latter being traced from battery 56, through lead 55, armature 34, lead 93, armature 69, lead 78, contact 76, armature 64, lead 94, the solenoid winding 70 60 and thence through leads 58 and 61, back to battery 56. The movable unit may now proceed through block D, but only with red light R energized and with the whistle sounding.

If the movable unit proceeds through block D and enters block C, relay R^5 will also become de-energized which in turn will de-energize relay 82 and consequently de-energize the train line valve solenoid 60, thereby causing the brakes to be applied a second time. In order again to release the brakes, push button 80B may be used to energize relay 82, closing the circuit of said relay from the battery 56, through lead 55, armature 35, lead 54, armature 30, lead 48, armature 25, lead 62, push button 80B, relay winding 82, leads 83, 84 and 61, back to the battery 56. The push button being released, relay 82 is held closed by armature 65 and its contact and lead 81 which bridge the push button 80B. The train line valve solenoid 60 is energized to release the brakes, as described above, when push button 80A was employed to energize the relay 82.

It will be noted that the circuits are so arranged that it requires the receiving of high frequency currents of three frequencies by the detectors of the movable unit to give a clear or safety indication. The receiving of any two frequencies will give a caution signal, indicating that the second block in advance is occupied, but the reception of but one frequency will give a danger indication, together with an application of brakes, and will indicate that the block next in advance is occupied. The absence of all frequencies will give a danger indication and a second brake application.

Assume the movable unit, the signal circuit of which has been just described, to be stationary. As the movable unit in advance thereof moves from block to block, the high frequency currents will be restored in their respective blocks and the movable unit in the rear will receive the proper indications, as will be understood from the previous description.

In order to make clear the functions and purposes of the circuits and apparatus of my invention, I have selected certain conditions which actually occur in practice. It is not deemed necessary or desirable in this specification to trace each and every circuit change that occurs under each and every condition that may occur in practice. The foregoing description is thought to be sufficiently clear to enable anyone skilled in the art readily to follow the functioning of the circuits and apparatus under every conceivable condition.

able condition that may arise in actual practice.

Figure 3 illustrates the application of my invention to single track operation, wherein 5 cars move in both directions over the same rails. In so far as concerns the way-side signals and the generators associated with the several trolley wire blocks, the arrangement of Figure 3 differs from that of Figure 2 10 only in that an additional high frequency generator is provided for each block, the frequencies delivered by these additional generators being indicated by subscripts, and in the further respect that way-side signals 15 are provided at each end of each block rather than merely at one end of each block, as is the case in double track operation. The arrangement of Figure 3 differs from that of Figure 2 in the further respect that by- 20 passes for the additional frequencies are provided around the insulating joints at the block ends.

In Figure 3 the additional high frequency generators are indicated as $G_{12,000}$, $G'_{14,000}$ 25 and $G'_{16,000}$, the subscripts indicating the frequencies delivered by the several additional generators. The additional by-passes are indicated by reference characters P' with suitable subscripts indicating the frequencies 30 to which they are tuned. The additional way-side signal poles are indicated at S' and it will be noted that the green, yellow and red lamps of the additional signal poles S' are controlled by the high frequency currents 35 of 12,000, 14,000 and 16,000 frequency to govern east-bound traffic in precisely the same manner as the signal lamps of the signal poles S are controlled by the currents of 5,000, 8,000 and 10,000 frequency to govern 40 west-bound traffic.

I contemplate that when my invention is applied to single track operation, each movable unit shall be provided with two sets of detectors, one set to be employed when the 45 movable unit is traveling in one direction and the other set to be used when the movable unit is traveling in the opposite direction. In Figure 3 the additional detectors which would be brought into play when the 50 direction of the west-bound car is changed, are indicated within the square 19, while the corresponding detectors of the east-bound unit are indicated within the square 19'.

I have endeavored to illustrate simplified, 55 rather than complex embodiments of my invention. It will be understood, of course, that in actual practice it may be desirable to have certain detectors more sensitive than will be possible when the circuit arrangements herein shown are followed in detail. When it is desirable that the detectors be 60 very sensitive, the use of an amplifier or a series of amplifiers in connection with any detector will of course, suggest itself to any- 65 one skilled in the art. For this reason, I

have not deemed it necessary to illustrate such amplifying devices. Furthermore, it will be understood that in certain cases it will not be feasible to have the windings of relays connected directly in circuit with the 70 detectors, particularly where the relays comprise a plurality of armatures and, therefore, require the application of considerable energy for their operation. In such cases the use of local circuits controlled by the detectors will readily suggest itself to those skilled in the art. In this connection I might suggest that the relays R^3 , R^4 and R^5 75 might very well be included in local circuits controlled by the detectors V^3 , V^4 and V^5 . 80

I wish to have it understood that when, in the appended claims, I refer to a trolley wire as the conductor through which propulsion and signaling current is supplied to a movable unit, the words "trolley wire" are 85 intended to cover a third rail or other equivalent means for carrying the currents mentioned.

Having thus described my invention, what I claim as new and desire to secure by Letters Patent of the United States, is:

1. A system of the class described comprising in combination with a section of a trolley wire, means for impressing a high frequency current thereon, a road-way signal apparatus comprising a high frequency detector connected with the said trolley wire section and adjusted to respond to the frequency impressed thereon, together with a movable unit provided with an audible signal comprising a high frequency detector electrically connected with the trolley wire section through a series resonant circuit, connection of the series resonant circuit of the vehicle with the trolley wire section intermediate the point of application of the high frequency current and the road-way signal apparatus serving to deprive the latter of the high frequency current aforesaid. 100

2. A system of the class described comprising in combination with a section of a trolley wire, means for impressing a high frequency current thereon, a road-way signal apparatus comprising a high frequency detector electrically connected with the trolley wire section, and a movable unit provided with signal apparatus comprising a high frequency detector also electrically connected with the trolley wire section, connection of the series resonant circuit of the vehicle with the trolley wire section intermediate the point of application of the high frequency current and the road-way signal apparatus serving to deprive the latter of the high frequency current aforesaid. 110

3. A system of the class described comprising in combination with a section of a trolley wire, means for impressing a high frequency current thereon, a road-way signal apparatus comprising a high frequency 120

- detector electrically connected with the trolley wire section, and a movable unit provided with signal apparatus comprising a high frequency detector also electrically connected with the trolley wire section, the detector of the road-way signal apparatus being excited through a parallel resonant circuit, the detector of the movable unit signaling apparatus being excited through a series resonant circuit.
4. In combination with a section of a trolley wire, means for impressing a high frequency current thereon, together with a road-way signaling apparatus comprising a high frequency current detector electrically connected with the trolley wire section, the said detector being excited from the trolley wire section through a parallel resonant branch circuit.
5. In combination with a section of a trolley wire and means for impressing a high frequency current thereon, a road-way signal apparatus comprising a high frequency detector permanently electrically connected with said trolley wire section, and a movable unit comprising signal apparatus including a high frequency current detector excited from the trolley wire section through a series resonant branch circuit, connection of the series resonant circuit of the vehicle with the trolley wire section intermediate the point of application of the high frequency current and the road-way signal apparatus serving to deprive the latter of the high frequency current aforesaid.
6. A system of the class described comprising a trolley wire divided into block sections, means for impressing a high frequency current upon each block section, the high frequency current impressed upon each block section being different in frequency from the high frequency current impressed upon the block next in advance thereof, tuned by-passes between adjacent block sections whereby each section may receive the high frequency current impressed upon the block section in advance, and a movable unit provided with signaling apparatus comprising a detector adapted to respond to each of the high frequencies employed.
7. A system of the class described comprising a trolley wire divided into block sections, means for impressing a high frequency current upon each block section, the high frequency current impressed upon each block section being different in frequency from the high frequency current impressed upon the block next in advance thereof, tuned by-passes between adjacent block sections whereby each section may receive the high frequency current impressed upon the block section in advance, a road-way signal associated with each block section, each road-way signal comprising a detector adapted to respond to the high frequency current im-

pressed upon its associated block section and also another detector adapted to respond to the high frequency current impressed upon the block section in advance of the section wherewith said last mentioned detector is connected.

8. A system of the class described comprising a trolley wire divided into block sections, means for impressing a high frequency current upon each block section, the high frequency current impressed upon each block section being different in frequency from the high frequency current impressed upon the block next in advance thereof, tuned by-passes between adjacent block sections whereby each section may receive the high frequency current impressed upon the block section in advance, a road-way signal associated with each block section, each road-way signal comprising a detector adapted to respond to the high frequency current impressed upon its associated block section and also another detector adapted to respond to the high frequency current impressed upon the block section in advance of the section wherewith said last mentioned detector is connected, together with a movable unit comprising signaling apparatus excited from whichever block section with which the vehicle is connected, said last mentioned signaling apparatus being excited through a series resonant circuit.

9. In combination with at least three successive sections of a trolley wire and means for impressing different high frequency currents on said sections and tuned by-passes between contiguous sections whereby one section may partake of the high frequency current impressed upon each of the two sections in advance thereof.

10. In combination with at least three successive sections of a trolley wire and means for impressing different frequency currents on said sections and tuned by-passes between contiguous sections whereby one section may partake of the high frequency current impressed upon each of the two sections in advance thereof, in combination with a movable unit comprising signaling apparatus including three high frequency current detectors, each of said detectors arranged to respond to one of the frequencies employed.

11. In combination with at least three successive sections of a trolley wire and means for impressing different frequency currents on said sections and tuned by-passes between contiguous sections whereby one section may partake of the high frequency current impressed upon each of the two sections in advance thereof, together with a movable unit comprising signaling apparatus including three high frequency current detectors, each of said detectors arranged to respond to one of the frequencies employed,

the signaling apparatus of the movable unit also comprising means adapted to give indication of "safety", "danger" and "caution" depending upon the number and relation of detectors excited at one time.

5 12. In combination with a trolley wire section, means for impressing a high frequency current upon one end thereof, and a road-way signal apparatus comprising a 10 high frequency current detector excited from the other end of the trolley wire section through a parallel resonant branch circuit.

13. In combination with a trolley wire 15 section, means for impressing a high frequency current upon one end thereof, a road-way signal apparatus comprising a high frequency current detector excited from the other end of the trolley wire section through a parallel resonant branch circuit, and a movable unit comprising a series resonant circuit adapted to divert the high frequency current away from the detector of the road-way signal apparatus when said series resonant circuit is connected with the trolley 25 wire section between the parallel resonant circuit and the source of high frequency current.

14. In combination with at least three successive sections of a trolley wire and means for impressing different frequency currents on said sections and tuned by-passes between contiguous sections whereby one section may partake of the high frequency current impressed upon each of the two sections in advance thereof, a movable unit comprising 35 signaling apparatus including three high frequency current detectors, each of said detectors arranged to respond to one of the frequencies employed, the signaling apparatus of the movable unit also comprising means adapted to give an indication of "safety" when the detectors of the movable unit are detecting three frequencies, an indication of "caution" when the said detectors are detecting two frequencies, and an indication of "danger" when said detectors are detecting but one frequency or no frequency.

15. A system of the class described comprising a trolley wire divided into block sections, means for impressing a high frequency current upon each section, the frequency of the currents impressed upon any successive three block sections being different, and tuned bypasses between contiguous sections whereby any section may partake of the high frequency currents impressed upon the two sections in advance thereof.

60 16. In a system of the class described, the combination with at least three successive block sections of a trolley wire, means for impressing different high frequency currents on said block sections, tuned by-passes connecting contiguous sections whereby one

section may partake of the high frequency current impressed upon the two block sections in advance thereof, choke coils adapted to carry propulsion current from one section to another, and road-way and movable unit 70 carried signals controlled by said high frequency currents to afford indications of danger, caution and safety.

17. In combination with a plurality of successive block sections, of a trolley wire 75 and tuned by-passes between contiguous sections, means for impressing high frequency currents of different frequency upon contiguous block sections, and a wayside signal apparatus associated with each block section 80 comprising a pair of detectors connected with that block section, one of each pair of detectors being responsive to the high frequency current impressed upon its associated block section and the other detector being responsive to the high frequency current impressed upon a contiguous block section. 85

18. In combination with a plurality of successive block sections, of a trolley wire 90 and tuned by-passes between contiguous sections, means for impressing high frequency currents of different frequency upon contiguous block sections, and a wayside signal apparatus associated with each block section 95 comprising a pair of detectors connected with that block section, one of each pair of detectors being responsive to the high frequency current impressed upon its associated block section and the other detector being responsive to the high frequency current impressed upon a contiguous block section, said detectors being excited through parallel resonant branch circuits. 100

19. In combination with a plurality of successive block sections, of a trolley wire 105 and tuned by-passes between contiguous sections, means for impressing high frequency currents of different frequency upon contiguous block sections, and a wayside signal apparatus associated with each block section 110 comprising a pair of detectors connected with that block section, one of each pair of detectors being responsive to the high frequency current impressed upon its associated block section, and the other detector being responsive to the high frequency current impressed upon a contiguous block section, together with means associated with each wayside signal arranged to indicate danger 115 when both detectors are de-energized, caution when but one is energized, and safety when both are energized. 120

20. A system of the class described, comprising in combination with sections of a trolley wire, means for impressing high frequency currents thereon, and a roadway signal apparatus comprising high frequency detectors connected with said trolley wire sections respectively and adjusted selectively to respond each to a definite frequency im- 125 130

pressed thereon, together with a movable unit comprising a high frequency detector adapted to be electrically connected with the trolley wire sections through a series resonant circuit, connection of the series resonant circuit of the vehicle with a trolley wire section intermediate the point of application of the high frequency currents and the roadway signal apparatuses serving to deprive the latter of the high frequency currents aforesaid.

21. A system of the class described comprising a conducting medium divided into block sections, means for impressing high frequency currents of different frequencies on each of three successive block sections, a movable unit arranged to move over said block sections, and signal controlling de-

vices carried by said movable unit responsive to said different frequencies, respectively.

22. A system of the class described comprising a conducting medium divided into block sections, means for impressing high frequency currents of different frequencies on each of three successive block sections, a movable unit arranged to move over said block sections, signal controlling devices carried by said movable unit responsive to said different frequencies, respectively, and signals controlled by said devices for indicating the occupied or unoccupied condition of a plurality of succeeding block sections.

In witness whereof, I hereunto subscribe my name this 11th day of June, 1920.

JOHN A. MILLER.
